(57) **CLAIM**

The ornamental design for a fitness wheel with rotating selector dial as shown and described.

DESCRIPTION

FIG. 1 is a perspective view of a fitness wheel with rotating selector dial according to our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the rotating selector dial for a fitness wheel shown in broken lines are for illustrative purposes only and form no part of the claimed design.

The dash-dash lines define the bounds of the claimed design and form no part thereof.

1 Claim, 7 Drawing Sheets
